UNITED STATES PATENT OFFICE.

CUNNINGHAM DRAKE, OF PHILADELPHIA, PENNSYLVANIA.

OYSTER-CLAMP.

SPECIFICATION forming part of Letters Patent No. 299,756, dated June 3, 1884.

Application filed May 2, 1884. (No model.)

To all whom it may concern:

Be it known that I, CUNNINGHAM DRAKE, a citizen of the United States, and a resident of Philadelphia, in the county of Philadelphia and State of Pennsylvania, have invented certain new and useful Improvements in Oyster-Clamps; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my oyster-clamp, showing the manner of using it. Fig. 2 is a longitudinal sectional view of the same. Fig. 3 is a cross-section on line *xx* in Fig. 2, and Fig. 4 is a perspective view showing the clamp open ready for the insertion of a bivalve.

Similar letters of reference indicate corresponding parts in all the figures.

In shucking oysters considerable difficulty is often experienced by the shucker in holding the oyster firmly and preventing it from slipping or from cutting the hands by the sharp flakes of its shells while it is being shucked; and my invention has for its object to form an inexpensive and convenient clamp for holding the oyster firmly during the operation of shucking.

This clamp consists of two parts, A and B, which may be made conveniently of any suitable wood or metal. One of the parts, A, constitutes the bottom part, which is longer than the top B, the two parts being connected at

their rear ends by any suitable hinge, C. The bottom A has a recess, D, rounded at its inner end, and gradually increasing in depth from the open front side, so as to form an inclined bottom, E. The top B has a similar horseshoe-shaped recess, F, with beveled or inclined sides, as shown at G. The recesses D and F are of such a shape that they will in a measure conform to the shape of that part of the oyster which is inserted into the clamp.

By reference to the drawings, the manner of using this device will readily be understood without further explanation. As the oyster is held between the hinged parts or jaws A and B, the projecting end may readily be cut with a knife or hammer and a pointed implement inserted for prying the shells apart. The clamp also prevents the hand of the shucker from being cut by the knife or opening-tool.

Having thus described my invention, I claim and desire to secure by Letters Patent of the United States—

The oyster clamp or holder consisting of the recessed bottom part, A, and short recessed top part, B, hinged together at C, the bottom part projecting beyond the top, as shown, substantially as and for the purpose set forth.

In testimony that I claim the foregoing as my own I have hereunto affixed my signature in presence of two witnesses.

CUNNINGHAM DRAKE.
